UNITED STATES PATENT OFFICE.

FRANK M. FREEBURG, OF PHILADELPHIA, PENNSYLVANIA.

RAILWAY-SWITCH.

1,193,887.

Specification of Letters Patent. Patented Aug. 8, 1916.

Application filed September 16, 1914. Serial No. 861,937.

To all whom it may concern:

Be it known that I, FRANK M. FREEBURG, a citizen of the United States, residing at Philadelphia, in the county of Philadelphia 5 and State of Pennsylvania, have invented certain new and useful Improvements in Railway-Switches, of which the following is a specification.

The object of my invention is to provide 10 a railway switch of novel, simple and efficient construction having provision, first, whereby it will be impossible for car wheel flanges to pass between the main track rail and the switch tongue when the latter is in 15 position to direct the wheels from the main track; secondly, whereby in one position of the mechanism, the side walls of the main track groove will be continuous and uninterrupted at the junction of the main track 20 groove and the branch groove, and, in another position of the mechanism, the side walls of the branch groove will be continuous and uninterrupted at the junction of the branch groove and the main track groove; 25 and, thirdly, whereby various novel and advantageous results are attained.

My invented devices consist of the elements and the combinations of them herein-after fully described and claimed.

30 In the accompanying drawings, illustrating my invention: Figure 1, is a plan view of a railway switch embodying my invention. Fig. 2, is a plan view of the two switch tongues removed from the switch structure. Fig. 3, is a longitudinal section, on line 3—3 of Fig. 1. Figs. 4, 5, 6 and 7 are transverse sections through the switch structure, on lines 4—4, 5—5, 6—6 and 7—7, respectively of Fig. 1. Fig. 8, is a transverse 35 section, on line 8—8 of Fig. 3. Fig. 9, is a horizontal section through a portion of the switch frame, showing the operating devices for the tongues and adjuncts. Fig. 10, is a perspective view of one of the cam shafts.

40 Referring to the drawings, 9 designates the frame of the switch structure having the main track groove 10 and the branch track groove 11 formed therein, the grooves 10 and 11 being adapted to receive the car 45 wheel flanges in the usual manner, the branch track groove 11 communicating with the main track groove 10. On the outside of the grooves 10 and 11 are the tread portions 12 and 13, and on the inside of the 50 grooves 10 and 11 are the guard portions 14 and 15, respectively, the guard portions 55

14 and 15 forming continuations of each other on one side of the branch groove 11 and the guard portion 14 and tread portion 13 forming a point portion 16 on the other 60 side of the groove 11 and separating the grooves 10 and 11.

Within the grooves 10 and 11 are two 65 tongues 17 and 18, respectively, each having a rounded end portion 19 fitted to turn in a socket 20 in the frame 9 in a manner to permit the pointed end of the tongue to be raised and lowered into and from the path of car wheel flanges. The tongue 17 has a vertical face 21 which, when the 70 tongue is raised, as shown, connects the side of the point portion 16 forming one wall of the branch track groove 11 with the side of the tread portion 12 forming one wall of the main track groove 10, so that when the 75 tongue 17 is up and the tongue 18 is down, as shown, the face 21 will direct wheel flanges from the main track groove 10 to the branch groove 11, and the side walls of the two grooves 10 and 11 will form uninterrupted continuations of each other.

The tongue 18 has a vertical face 22 which, when the tongue is raised, connects the side of the point portion 16 forming one 85 side of the guard portion 14 forming the same side of the main track groove 10, so that when the tongue 18 is up, and the tongue 17 is down, the face 22 will extend across the branch track groove 11, and both 90 side walls of the main track groove 10 will be continuous and uninterrupted, preventing wheel flanges from entering the branch track groove 11 from the main track groove 10.

The top of the point end of the tongue 95 17, is slightly below the top of the tread portion 12 and point portion 16, so that car wheels will not bear upon the tongue 17 when it is raised, the wheels being supported by both the tread portion 12 and point portion 16 in passing over the main track groove 10 to and from the branch track.

The pivoted end of each tongue is provided with a longitudinal groove 23 which is inclined upwardly and disappears at the 100 top of the point end of the tongue, the bottom of the groove 23 always being below the path of wheel flanges at the pivoted end of the tongue. Each tongue is fitted to slide vertically between two walls of the frame 110 9, and when each tongue is down its upper face forms a continuation of the floor por-

tions of the grooves beyond the ends of the tongue, and the floor of the main track groove is provided with a point portion 24 which extends between and separates the diverging faces 21 and 22 of the tongues 17 and 18, respectively.

To operate the switch, the tongues 17 and 18 are raised and lowered in alternate succession, and when the tongue 18 is raised, an uninterrupted main track groove is presented, and when the tongue 17 is raised, an uninterrupted branch track groove is presented. To thus raise and lower the tongues 17 and 18 I provide the following mechanism: 25 25 and 26 are vertical shafts which are mounted to turn in bearings in the frame 9. These shafts are located adjacent to the pointed ends of the tongues 17 and 18, respectively, and within a box 2 formed by the frame 9. 20 The shafts 25 and 26 carry sleeves 27 and 28, respectively. The sleeves 27 and 28 are provided with upper and lower cams 29 and 30 which, engage the adjacent ends of the switch tongues 17 and 18, as shown, and the 25 cams 29 and 30 of the two sleeves are so related to each other and to the tongues that when the sleeves are turned in the direction of the arrows in Fig. 9, the tongue 18 will be raised and the tongue 17 will be lowered, 30 and that when the sleeves are turned in the reverse directions, the tongue 18 will be lowered and the tongue 17 will be raised. The sleeves 27 and 28 are provided with co-acting gear wheels 31, so that when one 35 sleeve is turned in one direction the other will be turned in the reverse direction, as indicated by the arrows in Fig. 9, and engaging the teeth of one of the gear wheels 31 are the teeth of a gear rack 32 which is 40 mounted to slide in the frame 9. The rack 32 has an upwardly extending slotted lug 33, and extending into the slot in the lug 33 is a pin 34 which projects from an arm 35 on a head 36 which is rotatably mounted on a 45 pin or shaft 37 within the box 2. The head 36 has an opening or socket 38 therein for the reception of a bar or other device, by means of which the head 36 may be turned, and the socket 38 is exposed through an opening 39 in a plate or cover 40 for the box 2, to permit the insertion of the operating device. It will be readily understood that when the head 36 is turned, the pin 34 will engage the lug 33 and slide the rack bar 32 which will 50 55 turn the sleeves 27 and 28 for the operation of the switch.

I claim:

1. In a railway switch, the combination of a frame, a pair of vertically-movable switch tongues mounted therein, a pair of shafts

60 mounted to turn in said frame, cams on said shafts engaging said tongues, and gearing between said shafts.

2. In a railway switch, the combination of a frame, a pair of vertically-movable switch tongues mounted therein, a pair of shafts mounted to turn in said frame, cams on said shafts engaging said tongues, co-acting gear wheels on said shafts, a gear rack coacting with one of said gear wheels, and means operative to reciprocate said rack. 70

3. In a railway switch, the combination of a frame, a pair of vertically-movable switch tongues mounted therein, a pair of shafts mounted to turn in said frame, cams on said shafts engaging said tongues, coacting gear wheels on said shafts, a gear rack coacting with one of said gear wheels, a head mounted to turn in said frame, and means operated by said head for reciprocating said rack. 80

4. In a railway switch, the combination of a frame, a vertically movable switch tongue mounted therein, a shaft mounted to turn in said frame, a cam on said shaft engaging said tongue, a head mounted to turn in said frame, and gearing between said head and said shaft. 85

5. In a railway switch, the combination of a frame, a pair of vertically-movable switch tongues mounted therein, a pair of shafts mounted to turn in said frame, cams on said shafts engaging said tongues, gearing between said shafts, a head mounted to turn in said frame, and means operated by said head for turning said shafts. 95

6. In a railway switch, the combination of a frame, a vertically movable switch tongue mounted therein, and a rotatable part operative to force said tongue upwardly and to force said tongue downwardly in alternate succession. 100

7. In a railway switch, the combination of a frame, a vertically movable switch tongue mounted therein, a rotatable cam adapted to force said tongue upwardly, and to force said tongue downwardly in alternate succession, and means to turn said cam. 105

8. In a railway switch, the combination of a frame, a vertically movable switch tongue mounted therein, a cam adapted to force said tongue upwardly and to force said tongue downwardly in alternate succession, a vertical shaft carrying said cam, and means operative to turn said shaft. 110

In testimony whereof I affix my signature in presence of two witnesses.

FRANK M. FREEBURG.
